UNITED STATES PATENT OFFICE.

FRANCIS J. COLE, OF NEW YORK, N. Y., ASSIGNOR TO AMERICAN LOCOMOTIVE COMPANY, OF NEW YORK, N. Y., A CORPORATION OF NEW YORK.

SUPERHEATER.

No. 850,565.

Specification of Letters Patent.

Patented April 16, 1907.

Application filed April 30, 1906. Serial No. 314,348.

To all whom it may concern:

Be it known that I, FRANCIS J. COLE, of the borough of Manhattan, in the city and State of New York, have invented a certain new and useful Improvement in Steam-Boiler Superheaters, of which improvement the following is a specification.

My present invention relates to superheaters of the general class or type exemplified in Letters Patent of the United States, No. 782,490, granted and issued to the American Locomotive Company, as assignee of myself and Carl J. Mellin, under date of February 14, 1905; and its object is to provide in a superheating appliance means whereby the steam after having been superheated shall be effectually protected from the cooling action of the saturated steam in the passage of the latter from the boiler to and through the superheating appliances.

The improvement claimed is hereinafter fully set forth.

In the accompanying drawings, Figure 1 is a vertical longitudinal section through the forward portion of a locomotive-boiler, illustrating an application of my invention; Fig. 2, a vertical transverse section through the smoke-box, the right-hand half being taken on the line *a a* of Fig. 1 and the left-hand half on the line *b b* of the same figure; Fig. 3, a plan view, partly in section, of the T-head; and Fig. 4 a horizontal section, on an enlarged scale, through a portion of a superheating fire-tube, the superheater-pipes located in said tube, and the headers to which the front ends of said tubes are connected.

My invention is herein, as in Letters Patent No. 782,490 aforesaid, set forth as applied in connection with a locomotive-boiler 4, which is of the ordinary construction and is provided at its forward end with a smoke-box 4^a. A plurality of fire-tubes 4^c, ordinarily of comparatively small diameter, extend from the fire-box at the rear end of the boiler, which is not shown, to the front flue-sheet 4^d and the products of combustion pass through said tubes and through a number of tubes 67 of larger diameter, which are located in the upper and middle portion of the space within the boiler and which will be herein descriptively termed "superheating-tubes," to the smoke-box 4^a, from which they are discharged into the atmosphere

through a stack in the ordinary manner. Steam is supplied from the boiler to the cylinders through a main steam-pipe or dry-pipe 61, passing through the front flue-sheet 4^d and connected in front thereof to a transverse T-head 62, from which it is conducted through superheater-pipes 69, which with their connections will be presently described, and after being superheated in said pipes passes to the cylinders through branch steam-pipes 63, located on opposite sides of the smoke-box.

In the practice of my invention I locate in each of the superheating-tubes 67 one or more pairs (preferably, as shown, two pairs,) of superheater-pipes 69, said pipes extending longitudinally in the superheating-tubes 70 from a vertical plane a short distance—say thirty inches or thereabout—forward of the fire-box flue-sheet to vertical planes in the smoke-box forward of the front flue-sheet. The superheater-pipes of each pair are connected at their rear ends by return-bends or other suitable fittings and are held up in normal position in the superheating-tubes by any suitable and preferred supports.

The superheater-pipes are open at their forward ends, at which they are connected, as hereinafter described, with the main supply steam-pipe 61 and the branch or delivery steam-pipes 63, so as to constitute continuous avenues or channels throughout the length of which the steam which is to be superheated traverses from the supply steam-pipe to the branch or delivery steam-pipes. To this end I provide a T-head, which comprises a supply-compartment 62, 90 to which the main supply-pipe or dry-pipe 61 is connected in the usual manner, and a delivery-compartment 62^f, located in front of the supply-compartment and separated therefrom by an intervening space, to the 95 ends of which compartment the branch or delivery steam-pipes 63 are connected. A plurality of vertical saturated steam-headers 70 and superheated steam-headers 70^f extend downwardly from the supply and the delivery T-head compartments, respectively, and communicate therewith at their upper ends, the headers being preferably, as shown, integral with the respective T-head compartments. In the instance shown the supply and delivery T-head compartments 62

and 62^r are formed integral and connected by narrow webs 62^g; but they may, if desired, be made of separate castings having projections on their front and rear sides, respectively, which are planed and faced off on a machine and abut so as to insure their registration and proper location relative to the front and rear compartment-castings. The saturated and the superheated steam-headers are alternated in position or located in different vertical planes on the compartments of the header with which they respectively communicate, as clearly shown in Fig. 3, and their walls are entirely out of contact with another and are exposed throughout to the heat of the smoke-box gases.

The forward end of one of the superheater-pipes 69 of each pair is expanded into the rear of the saturated steam-header 70 of the vertical row of superheating-tubes in which the pair is located and the forward end of the other pipe of each pair is similarly connected to the rear of the superheated steam-header 70^r of the same vertical row. Openings which are closed by removable plugs 70^e are formed in the fronts of the headers, said openings providing for the insertion, examination, cleansing, and repairs of the superheater-pipes. In the event of leakage at the joints the plugs can be detached and the pipes expanded as required.

In operation saturated steam from the boiler passes through the dry-pipe 61 into the supply-compartment 62 of the T-head, and thence into the communicating saturated steam-headers 70, from which it passes first rearwardly and then forwardly through the connected superheater-pipes 69 and thence into and through the superheated steam-headers 70^r, being in its traverse through the headers and superheater-pipes thoroughly superheated by the hot products of combustion which pass through the inclosing superheating-tubes and through the smoke-box. The superheated steam passes from the superheated steam-headers 70^r into the communicating delivery-compartment 62^r of the T-head and thence through the branch steam-pipes 63 to the engine-cylinders for utilization therein.

By reason of the substantially complete separation of the walls of the supply-compartment of the T-head from those of the delivery-compartment thereof and of the complete separation of the walls of the saturated steam-headers from those of the superheated steam-headers loss of heat which would result from its transfer through said walls from the superheated to the saturated steam is effectually prevented. The form and location of the headers are also such as to expose a large area of effective heating-surface to the action of the hot products of combustion passing through the smoke-box.

I claim as my invention and desire to secure by Letters Patent—

1. The combination, with a tubular steam-boiler, of a superheating-tube, a pair of superheater-pipes extending longitudinally therein and connected at their rear ends, a vertical saturated steam-header located in front of the superheating-tube and connected to the forward end of one of the pair of superheater-pipes, a similarly located vertical superheated steam-header having its walls entirely separated from those of the saturated steam-header and connected to the forward end of the other superheater-pipe, and a T-head comprising a supply-compartment 75 communicating with the saturated steam-header and a delivery-compartment communicating with the superheated steam-header.

2. The combination, with a tubular steam-boiler, of a superheating-tube, a pair of superheater-pipes extending longitudinally therein and connected at their rear ends, a vertical saturated steam-header located in front of the superheating-tube and connected to the forward end of the pair of superheater-pipes, a similarly located vertical superheated steam-header having its walls entirely separated from those of the saturated steam-header and connected to the forward end of the other superheater-pipe, and a T-head 85 comprising a supply-compartment communicating with the saturated steam-header and a delivery-compartment communicating with the superheated steam-header.

3. The combination, with a tubular steam-boiler, of a vertical row of superheating-tubes, pairs of superheater-pipes extending longitudinally therein, fittings connecting the ends of the pipes of each pair nearer the firebox, a main steam-supply pipe, a steam-delivery pipe, a vertical saturated steam-header and a vertical superheated steam-header located in front of the row of superheater-tubes, having entirely separated walls, and communicating, respectively, with the receiving and the delivery ends of the steam-channels formed by the vertical row of pairs of superheater-pipes, and a T-head comprising a supply-compartment communicating with the steam-supply pipe and with the saturated steam-header and a delivery-compartment communicating with the superheated steam-header and with the steam-delivery pipe.

4. In a steam-boiler superheater, the combination of superheating-tubes, pairs of superheater-pipes extending longitudinally therein and constituting steam-channels, a T-head structure comprising a supply-compartment communicating with a steam-supply pipe and a delivery-compartment communicating with a steam-delivery pipe and

having its wall which is adjacent to that of the supply-compartment separated therefrom by an open space, a plurality of vertical saturated steam-headers extending downwardly from the T-head supply-compartment and connected on their rear sides to the receiving ends of the steam-channels, a plurality of vertical superheated steam-headers extending downwardly from the T-head delivery-compartment and having their walls entirely separated from those of the saturated steam-headers, said superheated steam-headers being connected on their rear sides to the delivery ends of the steam-channels, and removable plugs closing openings in the front sides of the headers opposite the ends of the superheater-pipes.

5. In a steam-boiler superheater, the com-

bination of a T-head structure comprising a supply-compartment communicating with a steam-supply pipe and a delivery-compartment located in front of the supply-compartment and communicating with a steam-delivery pipe, a plurality of saturated steam-headers extending downwardly from the supply-compartment, a plurality of superheated steam-headers extending downwardly from the delivery-compartment, and a plurality of superheater-pipes forming steam-channels, the opposite ends of which are connected to the rear side of the saturated and the superheated steam-headers, respectively.
